United States Patent Office

Des. 175,896
Patented Oct. 25, 1955

175,896

SAFETY RAZOR GUARD

William P. MacMicking, Minneapolis, Minn.
Application June 17, 1955, Serial No. 36,572

Term of patent 14 years

(Cl. D22—3)

FIG.1.

FIG.2.

Figure 1 is a top perspective view of a safety razor guard showing my new design and Figure 2 is an enlarged fragmentary perspective view thereof.

I claim:

The ornamental design for a safety razor guard, substantially as shown.
